UNITED STATES PATENT OFFICE

2,619,906

LIQUID LEVEL CONTROL MECHANISM

Allen J. Gardenhour, Waynesboro, Pa.

Application September 7, 1944, Serial No. 553,097

2 Claims. (Cl. 163—25)

1

This invention relates to improvements in liquid level control mechanisms.

The primary object of this invention is the provision of an improved liquid level automatic pump control mechanism.

A further object of this invention is the provision of an improved steam boiler automatic water level control mechanism.

Other objects and advantages of the invention will be apparent during the course of the following detailed description.

In the accompanying drawings, wherein for the purpose of illustration are shown different forms of the invention:

Figure 1 is a side elevation, partly diagrammatic, showing the improved liquid level and alarm mechanism associated with means for automatic pump control.

Figure 2 is a diagrammatic view of the wiring of the control mechanism shown in Figure 1.

Figure 3 is a side elevation, partly diagrammatic, showing the improved liquid level control and alarm mechanism associated as an automatic water level control on steam boilers.

Figure 4 is a wiring diagram of the set up shown in Figure 3.

As a general feature of the liquid level control mechanisms shown in Figures 1 and 3 of the drawings, I provide a cylindrical shaped tank 20 having a compartment therein intended to receive liquid from a storage tank or boiler, as the case may be. This tank is pivotally mounted upon a supporting platform or base structure, eccentrically, as shown in Figures 1 and 3, so that when liquid is disposed therein one end of the container will be over balanced, which is the left end as is shown in Figures 1 and 3. I have provided adjusting means to limit the angle or tilt of the container 20, and this consists of an adjusting screw 40 as shown in Figure 1. Also a second screw 42 may be adjustably threaded in the platform structure, indicated at 24 in Figure 3, and 24^b in Figure 1, at the opposite side of the pivot of the tank, for also regulating the degree of tilt of the tank. The second screw may be positioned so that the tank 20 will not be exactly horizontal when it returns to position so that the ball member, which is a weight disposed in the container 20, will roll from the dispensing end of the tank to the opposite end thereof. Means is provided to move the tank after a dispensing or flow of liquid therefrom to a dangerously low level and this consists of a spring 50 adjustably connected between the platform and a bracket upon the tank 20. The tension of the spring of course may be increased or decreased.

2

A switch 60 as shown in Figure 1, or 60^b as shown in Figure 3, of the mercury type is mounted upon a bracket of the tank 20 for controlling a circuit. Of course this mercury switch is of the usual detachable type.

In Figures 1 and 2, the mechanism is shown applied to a water storage tank which is automatically pump controlled. The water storage tank 130 is provided with a gauge glass 131. The storage tank has a suitable water inlet connection 132 and any desired outlet connection (not shown). The tank has a compressed air space 133 above the normal water level which is indicated at 134.

The liquid level control tank 20 is mounted upon a bracket structure 24^b which is secured to the tank 130 in the manner shown. The tank 20 is connected by a flexible tube 135 with the space 134 of the tank so that the same pressure exists in the container 20 above the liquid level therein as exists in the water storage tank. The outlet duct 23 is connected by flexible tubing 136 with the water storage tank below the normal level of water therein. The mercury bulb 60 is positioned in a clip structure upon the container 20 so that the mercury therein will not close the contacts of the mercury bulb when the level of water in the storage tank is normal; it being intended that the switch will close under influence of the spring 50 which will tilt the container 20 when the level in the water storage tank drops below the desired level. The binding posts 66 are connected by means of wires 140 leading to an electric motor 141 which operates a motion translating device 142 connected to a pump. The pump is operated by the motor upon closing of the circuit 140 for the purpose of pumping water into the tank thru the line 132.

Figures 3 and 4 show the application of the liquid level control mechanism for automatically controlling the water level in a steam boiler. The steam boiler is indicated at 150 and the liquid level control bracket 24 is mounted upon the steam boiler. A gauge glass 151 is positioned upon the boiler 150. To the bottom thereof the outlet extension 23 is connected by flexible tubing 152. The vent opening of the tank 20 is connected by flexible tubing 153 with the top of the gauge glass 151 so that the same pressure will exist in the top of the tank 20 as exists in the steam boiler above the water level. The mercury switch bulb 60^b, during normal level in the steam boiler, is open and only when the water level drops in the steam boiler will the switch close under influence of tilting of the container 20 in the manner above described. In the circuit with

the mercury bulb is an electric motor 154. The latter operates a pump 155 for supplying water through line 156 to the boiler. The line 156 may have a check valve 157 therein. The steam boiler may be heated by means of a motor operated burner 170. While the drawing does not show pressure controls for the boiler and room thermostat it is understood, as shown in the wiring diagram of Figure 4, that the circuit 160, in addition to the switch 60^a, may have other pressure control and room thermostat switches 161 and 162 in any desired number.

Various changes in the shape, size and arrangement of parts may be made to the form of invention herein shown and described without departing from the spirit of the invention or scope of the following claims.

I claim:

1. In a liquid storage tank control mechanism the combination of a liquid storage tank, motor actuated pump means for supplying liquid to the tank, a pivoted container having a compartment therein, means mounting the container with respect to the tank so that the upper portion of the compartment will lie above the normal desired liquid level in the storage tank, said container mounting means consisting of an eccentric pivot for said container, a flexible line connecting the upper portion of the compartment of the container with the storage tank above the liquid level therein, flexible conduit means connecting the lower portion of the compartment of said container with the water storage tank below the liquid level therein, the container being so mounted on its pivot that the level of liquid in the container complementary to the normal liquid level in the storage tank will predetermine the position of the container, a circuit for the motor, and switch means associated with said container normally open during normal liquid level therein and adapted to be closed upon movement of the container as a result of dropping of liquid level therein to place said motor in operation for pumping water into the storage tank, and coun-

terbalancing means to move the container for closing said switch when the liquid level in the container and tank have dropped below normal.

2. In a liquid level regulating mechanism for steam boilers and the like, the combination of a steam boiler, a pivoted container mounted upon said steam boiler eccentrically between the ends thereof, inlet and outlet connections for the container respectively connected directly with the steam boiler outer compartment above the water level and below the water level, liquid supply water actuated pump means including a circuit, a movement operated switch for the circuit mounted upon said container for closing the circuit when the level of liquid drops below normal, and counterbalancing means to move the container when the liquid level so drops.
